UNITED STATES PATENT OFFICE.

ARCHIBALD DUTHIE, OF INDIANAPOLIS, INDIANA, ASSIGNOR OF ONE-HALF TO THE H. LIEBER COMPANY, OF INDIANAPOLIS, INDIANA, A CORPORATION OF INDIANA.

FLASH-LAMP.

SPECIFICATION forming part of Letters Patent No. 733,705, dated July 14, 1903.

Application filed February 8, 1902. Renewed June 6, 1903. Serial No. 160,421. (No model.)

To all whom it may concern:

Be it known that I, ARCHIBALD DUTHIE, a citizen of the United States, residing at Indianapolis, in the county of Marion and State 5 of Indiana, have invented certain new and useful Improvements in Flash - Lamps, of which the following is a specification.

My invention relates to an improvement in lamps for the production of a flash-light for 10 photographic purposes.

The object of my invention is to produce a simple and efficient lamp which may be operated from a distance, if desired, the ignition of the powder being accomplished by the explosion of a fulminating-cap, preferably paper caps commonly used in toy pistols and the like.

The accompanying drawings illustrate my invention.

Figure 1 is a perspective view of a desirable form of my invention operable from a distant point. Fig. 2 is an enlarged section detail thereof. Fig. 3 is a sectional detail of a modified form for use as a hand-lamp. Fig. 25 4 is a detail of the means for exploding the paper caps.

In the drawings, 5 indicates a straight tube, within which is reciprocably mounted a piston 6. Leading into the lower end of tube 5 is a small tube 7, to which is attached a pipe or flexible hose 8, provided at its outer end with a bulb 9. The lower end of tube 5 is closed by cap 10, to which is secured a tube or rod 11, which may telescope within a tube 35 12. Tube 12 may telescope within the tubular portion 13 of a stand 14, which is preferably of the folding type. The upper end of tube 5 is preferably removably screwed into a coupling 15, carried by the powder-pan 40 16, which may assume any desired form. For many reasons I prefer a trough-like pan, such as is shown in Fig. 1. The interior of coupling 15 forms a continuation of the bore of tube 5, and extending across said opening is 45 a bar 17, sufficient space being left beneath the lower edge of said bar and the bottom of pan 16 to allow the insertion of a cap 18. In order to avoid all possibility of any flash-powder getting down into the tube 5, it is 50 desirable that the piston 6 does not come into direct contact with the cap 18, and for this reason I mount in coupling 15 a reciprocable

hammer 19, said hammer being provided at its upper end with an enlarged portion, which rests upon the upper end of the tube 5, and 55 thus forms a perfect guard to prevent any powder from passing into the tube. The upper end of hammer 19 is normally held in line with or slightly below the bottom of pan 16, the arrangement being such that it will 60 be movable within coupling 15 when tube 5 is secured thereto.

The construction in the hand-lamp shown in Fig. 3 is identical with the construction already described, except that a bulb 21 is 65 secured to the lower end of tube 5 and tube 7 is omitted. In this form the bulb 21 forms the handle for the device, and the downward movement of piston 6 is limited by a suitable shoulder 22.

In order to prevent the piston 6 from making a noise when it drops, a suitable cushion-spring 24 may be placed in the lower end of the tube 5.

In operation piston 6 lies normally at the 75 lower limit of its movement in tube 5 and hammer 19 also lies at the lower limit of its movement in coupling 15. A cap 18 is then placed between hammer 19 and the lower edge of bar 17 and a sufficient quantity of powder 80 23 placed in the pan so as to cover bar 17 and come into contact with the cap 18. By compressing bulb 9 (or bulb 21 in the hand-lamp shown in Fig. 3) the piston 6 will be propelled 85 upward through tube 5, so as to strike hammer 19 and move said hammer upward with sufficient force to drive the cap 18 against bar 17 and explode the same, so as to ignite the charge of powder. As soon as the pressure upon the bulb is released the piston 6 90 and hammer 19 drop back to their normal positions and the lamp is ready to be reloaded.

I claim as my invention—

1. A flash - lamp consisting of a tubular body, a powder-pan, lying substantially at 95 right angles to the tubular body secured to one end of said body and provided with an opening communicating with the interior of the tubular body, a piston mounted in said body and capable of reciprocation therein, a 100 cross-bar carried by the powder-pan across its opening in position to allow the insertion of a percussion-cap therebeneath, a guard arranged between the pan and the upper end

of the tube, and means for compressing the air in the tube behind the piston.

2. A flash-lamp consisting of a tubular body, a powder-pan secured to the upper end 5 of the body and having an opening communicating with the interior thereof, said powder-pan lying substantially at right angles to the tube, a cross-bar carried by the powder-pan in position to allow a percussion-cap to 10 be inserted beneath it and in line with the opening, a hammer supported in the upper end of the tube between the cross-bar and the upper end of the tube, a piston mounted in the tube beneath the hammer and adapted 15 to be reciprocated within the tube, and means for compressing the air in the tube behind the piston.

3. A flash-lamp consisting of a tubular body 5, a powder-pan 16 detachably secured

to the tubular body and having an opening 20 in its bottom in alignment with the bore of the body, a cross-bar extending across said opening, a hammer 19 mounted in alignment with the bore of the body and supported upon the upper end thereof beneath the opening 25 and cross-bar, a piston 6 mounted in the body beneath the hammer, and a compressible air-bulb 9 communicating with the interior of the body 5 beneath the piston, all substantially as and for the purpose set forth. 30

In witness whereof I have hereunto set my hand and seal, at Indianapolis, Indiana, this 4th day of February, A. D. 1902.

ARCHIBALD DUTHIE. [L. S.]
